CAP CONSTRUCTION

Julius Carlson, Brooklyn, N. Y.

Application August 2, 1952, Serial No. 302,338

3 Claims. (Cl. 2—172)

1

This invention relates to caps. It is particularly directed to caps provided with earlaps. Caps with earlaps as heretofore made, usually had the earlaps stitched to the lower edge of the crown of the cap. Such construction caused a bulkiness at the lower edge of the crown. Furthermore, with such construction the ears had to be flattened against the head and tucked underneath the crown so as to get the earlaps down over the ears without bending or cramping the ears.

It is, therefore, an object of the present invention to obviate the above mentioned difficulties encountered with present caps by attaching earlaps to the crown at points spaced substantially above the lower edge of the crown.

Another object of this invention is to provide a cap of the character described, comprising a crown and a visor attached to the crown, a back band stitched to the crown from one end of the visor all around the back of the crown to the opposite end of the visor, and earlaps attached to the upper edge of the back band on opposite sides of the cap.

Another object of this invention is to provide a cap of the character described, in which the back band is attached at its lower edge to the lower edge of the crown, and said band being otherwise free of the crown, but detachably attached thereto by means of buttons on the crown passing through buttonholes at the forward ends of the back band.

Yet a further object of this invention is to provide a cap of the character described, comprising a crown with a visor, a back band stitched to the crown, earlaps attached to the upper edges of the back band, and a second band interconnecting the earlaps and foldable down together with the earlaps.

Yet another object of this invention is to provide a cap to which is attached a back band and earlaps detachably attached to the back band so that they may be easily removed therefrom.

Still a further object of this invention is to provide a strong, durable cap of the character described, which will be relatively inexpensive to manufacture, easy to manipulate, comfortable to wear, and yet practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described,

and of which the scope of invention will be indicated in the following claims.

In the accompanying drawings in which is shown various illustrative embodiments of this invention:

Fig. 1 is a top perspective view of a cap embodying the invention with the earlaps folded over;

Fig. 2 is a cross-sectional view through an earlap and part of the crown of the cap in Fig. 1;

Fig. 3 is a view similar to Fig. 1 but illustrating a modification;

Fig. 4 is a cross-sectional view through an earlap and a portion of the crown of the cap shown in Fig. 3;

Fig. 5 is a partial view similar to Fig. 3 but illustrating yet another modification;

Fig. 6 is a cross-sectional view through an earlap and part of the crown of the cap shown in Fig. 5; and

Fig. 7 is a partial perspective view illustrating yet another modified construction.

Referring now in detail to Figs. 1 and 2 of the drawing, 10 designates a cap embodying the invention. The same comprises a crown 11 to which is fixed in the usual manner, a visor 12.

Stitched to the crown of the cap and extending upwardly from the lower edge thereof, is a back band 13. The back band 13 has its lower edge stitched as by stitching 14 to the lower edge of the crown. The back band 13 terminates at opposite sides adjacent the rear ends of the visor 12. Its upper edge and front ends are stitched as by stitching 15 to the crown.

Attached to the upper ends of the back band 13 at the sides of the hat are a pair of earlaps 16. The earlaps 16 may have a fur or wool piling or other soft material 17 at its outer surface (when the laps are folded upwardly). The rear ends 40 of the laps 16 are interconnected by a second back band 18 which is foldable away from the crown together with the earlaps 16.

It will now be observed that the laps 16 together with the back band 18 may be folded downwardly. Such construction removes bulkiness from the lower edge of the crown. Furthermore, sufficient room is given for the ears to project above the lower edge of the crown without necessity for the ears to be crushed or bent by the earlaps.

A strap 20 may be stitched to one end of the lap 16 for attachment by snap fastener means 21 on a buckle 22. The snap fastener 21 on the buckle 22 may be a female fastener for attach-

ment to a male fastener 23 on the opposite earlap 16.

In Figs. 3 and 4 there is shown a cap 10a similar to the cap 10 except that the upper or second back band 18 of cap 10 is omitted and the back band 13a of cap 10a which corresponds to the back band 13 of Fig. 1, while being stitched at its lower edge to the crown by stitching 14a, is free of the crown at its upper end. However, the back band 13a may be provided at its forward ends with button holes 25 to receive buttons 26 stitched as at 27 to the crown of the cap.

In Figs. 5 and 6 there is shown a cap 10b embodying the invention and illustrating a further modification. Cap 10b is similar to the cap 10 with the exception that the back band 18 is omitted.

In Fig. 7 there is shown a cap 10c embodying the invention and illustrating another modification. The cap 10c comprises a visor 12 attached to a crown 11. Stitched to the crown is a back band 13. Stitched to the sides of the back band are buttons 20. Detachably attached to the buttons 20 are earlaps 21. The earlaps 21 are formed with button holes 22 to receive the buttons 20.

It will be noted that the earlaps 21 are detachably attached and easily removable. Snap fasteners or other quickly detachable fastening means may be substituted for the buttons and button holes.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A cap comprising a crown adapted to receive the head and adapted to extend downwardly at the sides of the head with its lower edge adjacent the upper ends of the ears of the wearer, a pair of earlaps, each having an edge portion attached to the sides of the crown above the lower edge of the crown, each of the earlaps and its attached edge portion, when in the inoperative position, extending downwardly towards the lower edges of the crown and lying flat thereagainst, the flaps being foldable downwardly about the attachments

between the earlaps and the crown into an operative ear covering position, the folds in the earlaps forming pockets adapted to receive the upper ends of the ears of the wearer.

5 2. A cap comprising a crown adapted to receive the head of a wearer and adapted to extend downwardly at the sides of the head to an area below the upper ends of the wearer's ears, a pair of earlaps, each having an edge portion attached to the sides of the crown above the lower edge of the crown, each of said earlaps and its attached edge portion when in an up and non-ear covering position extending downwardly towards the lower edges of said crown and lying flat thereagainst, said earlaps being foldable downwardly about the attachments between the earlaps and the crown from said non-ear covering position to an ear covering position, the folds in the earlaps when said earlaps are folded downward to an ear covering position forming pockets to receive the upper ends of the ears of the wearer.

15 3. A cap comprising a crown adapted to receive the head of a wearer and adapted to extend downwardly at the sides with the lower edge thereof adjacent the upper ends of the wearer's ears, a pair of earlaps each having an edge portion attached to sides of the crown above the lower edge of the crown, said earlaps being adapted to lie against the crown above the points of attachment thereof when in an up and non-ear covering position, said earlaps being flexible and foldable out and down from said non-ear covering position to an ear covering position, said folding of said earlaps producing substantially 180° folds therein adjacent the ends attached to said crown and above the lower edge of said crown, the folds in the earlaps forming pockets adapted to receive the upper ends of the ears of the wearer.
